UNITED STATES PATENT OFFICE

158,354

SUITCASE OR THE LIKE

Samuel Bert, Dallas, Tex.

Application September 20, 1948, Serial No. 148,657

Term of patent 14 years

(Cl. D87—5)

To all whom it may concern:

Be it known that I, Samuel Bert, a citizen of the United States, residing at Dallas, in the county of Dallas and State of Texas, have invented a new, original, and ornamental Design for a Suitcase or the like, of which the following is a specification, reference being had to the accompanying drawing, forming part thereof.

In the drawing:

Fig. 1 is a perspective view of a suitcase, showing my new design;

Fig. 2 is a perspective view showing the opposite side of the suitcase.

My design for a suitcase is characterized by the diamond shaped side ornamentation in association with the handle and latching elements on the top of the suitcase and the rounded corner reinforcements, all as shown in the drawing.

I claim:

The ornamental design for a suitcase or the like, as shown and described.

SAMUEL BERT.
